DESIGN FOR A GARMENT HANGER

Louis M. Marble, Canton, Pa.

Application November 27, 1941, Serial No. 104,357

Term of patent 3½ years

To all whom it may concern:

Be it known that I, Louis M. Marble, a citizen of the United States and a resident of Canton, in the county of Bradford and Commonwealth of Pennsylvania, have invented a new, original, and ornamental Design for Garment Hangers, of which the following is a specification, reference being had to the accompanying drawing, forming part thereof.

Fig. 1 is a view in front elevation of a garment hanger, showing my new design, and

Fig. 2 is a view of the hanger in end elevation.

I claim:

The ornamental design for a garment hanger, as shown.

LOUIS M. MARBLE.
